UNITED STATES PATENT OFFICE.

ARNOLD V. BROWN, OF WORCESTER, MASSACHUSETTS, ASSIGNOR TO AMERICAN NARROW FABRIC COMPANY, A CORPORATION OF MASSACHUSETTS.

BUCKLE BASE.

Application filed July 22, 1922. Serial No. 576,783.

To all whom it may concern:

Be it known that I, ARNOLD V. BROWN, a citizen of the United States, residing at Worcester, in the county of Worcester and 5 State of Massachusetts, have invented a new and useful Buckle Base, of which the following is a specification.

This invention relates to a base for a buckle for use on hose supporters, suspenders, and other articles of personal wear for binding two pieces of tape or the like together.

The principal objects of the invention are to provide a base for the clamping plate in 15 such form that the base can be stamped out of sheet metal with a pair of arms located adjacent to the ends of the base and in the plane thereof, and these arms then can be bent up from the base to form two opposite 20 pivots in alignment with each other for the clamping plate; to provide these parts in such form that there will be very little metal wasted in the process of stamping out the parts, and the arms can be bent up very 25 readily and inexpensively so that the edges of the buckle are smooth all around and without any projections; and to provide a construction of the base that will be very inexpensive both as to the amount of material used and the operation of producing it.

Reference is to be had to the accompanying drawings in which—

Fig. 1 is a plan of a blank stamped out 35 flat from which the buckle is to be made;

Fig. 2 is an end view of the same;

Fig. 3 is a view similar to Fig. 1 showing the base in its complete form made from said blank;

Fig. 4 is an end view of the same;

Fig. 5 is an edge view of the same showing the clamping plate in position, that is, it shows the complete buckle; and

Fig. 6 is a perspective view of the base 45 without the clamping plate.

In order to secure the above mentioned advantages, I stamp out of a piece of sufficiently thick sheet metal a flat plate 10, which is to constitute the base plate of the 50 buckle. This is provided in whatever shape may be desired, and at its ends are two oppositely projecting arms 11. One edge of each of these arms is in alignment with the edge

of the base plate 10, and there is no need of these arms extending beyond this line. Each 55 one of them extends inwardly toward the opposite edge of the base and then the two ends 12 of these arms extend inwardly toward each other and in alignment. These arms, therefore, as the device is originally stamped 60 out of a piece of sheet metal, are located just beyond the ends of the plate and project toward them so that very little metal is wasted in the stamping operation, not much more than would be wasted with that particular 65 shape of base plate if the arms were not used in fact. This stamping having been made it is put into a bending die or other apparatus and the two arms 11 are twisted at the points where they join the base 10 around into a 70 plane substantially at right angles to that base, so that both of them are in the same plane, and the two projections 12 extend toward each other. These two projections then are in alignment and constitute the 75 pivots on which the eyes 13 of the clamping plate 14 are mounted to permit the pivotal motion of this clamping plate which is required in a buckle of this character.

It is to be noted that the plane in which the arms 11 and pivot ends 12 are located in the completed article is preferably not exactly at right angles to the base plate 10, but at an angle slightly less acute. This is to bring the pivots over the base plate instead of having them over the edge thereof. The buckle is used in the usual way as will be understood. The two pivot ends 12 are all that is needed to hold the clamping plate against removal as it is mounted on them by 85 bending its two eyes over them in the usual way.

By providing for manufacturing the device as stated the loss of considerable metal in the stamping operation is avoided, each base plate being stamped out of a rectangular piece, only very small portions of which are discarded and the dimensions of which are at a minimum for this kind of a device. The arms which project out of the plane of the 100 base plate are formed from portions of the blank, most of which would have to be thrown away even if the arms were formed in some other way on account of the fact that the ends of the base plate converge. 105 Such a base plate is smooth at the edges and

entirely without projections after it is finished. It is sufficiently strong for the purpose intended, light, and durable, and the cost of manufacture and stock is very materially reduced by this procedure.

Although I have illustrated and described only a single form of the invention I am aware of the fact that modifications can be made therein by any person skilled in the art 10 without departing from the scope of the invention as expressed in the claim.

Therefore I do not wish to be limited to all the details of construction herein shown and described, but what I claim is:—

15 As an article of manufacture, a blank for a buckle base plate comprising a flat plate of sheet metal furnishing a broad surface for receiving and supporting a tape thereon in flat condition, having diverging ends and

provided with two opposite flat arms projecting in the same plane, from the edges of said ends, at a distance from each edge of said plate, said arms extending at right angles therefrom and then extending inwardly toward each other to form two pivot ends in alignment with each other at a distance from the point at which the arms are connected with the plate, whereby said arms are located largely in the space left by the shaping of the ends of the plate to diverge from each other, and whereby said arms can be bent away from the plate at any desired angle, leaving their ends in alignment with each other and at a distance from the plate to constitute pivots for a clamping plate. 30 35

In testimony whereof I have hereunto affixed my signature.

ARNOLD V. BROWN.
